WEAVING DEVICE

Donald R. Simonds, Winchester, Mass., assignor
to Donar Products Corporation, Osterville,
Mass., a corporation of Massachusetts

Application January 4, 1949, Serial No. 69,089

1 Claim. (Cl. 28—15)

1. **My invention relates to a device for simplifying the hand weaving of articles of clothing and the like, particularly woolen articles such as sweaters, shawls, blankets, afghans, etc.**

The invention aims to provide a device of the indicated character which is suited for use by individuals having little, if any, previous knowledge of the weaving art; which is adapted to the weaving of both plain weaves and weaves of special design; which enables the accomplishment of a given weave in less time than is required using devices heretofore proposed; which is light in construction and, accordingly, easily handled and manipulated, and which may be manufactured at low cost from a variety of materials.

Other objects will appear from the following description which will proceed with reference to the accompanying drawings illustrating a preferred embodiment of the invention and in which:

Fig. 1 is a full scale plan view of one form of the device, the view showing part of a standard weave;

Fig. 2 an enlarged view on the lines indicated in Fig. 1; and

Fig. 3 an enlarged fragmentary perspective view.

Numerals 10 in the drawings denotes, generally, a square frame member having a plurality of pins 11 on its working face, the pins on each side of the frame being in alignment and being arranged, for the most part, in spaced groups of three. For convenience in use of the device, three of the four corners of the frame are provided with direction arrows and are numbered.

The row of pins extending between corners 1 and 2 terminates at the number 1 corner in a four-pin group and at the number 2 corner in a two-pin group. Similarly, the row of pins between the unnumbered corner and the number 3 corner ends in a four-pin group at the unnumbered corner and in a two-pin group at the number 3 corner. The end groups, in the case of the row extending from the number 1 corner to the number 3 corner, are constituted of three pins and two pins, respectively, while the row between the number 2 corner and the unnumbered corner terminates at the unnumbered corner in a three-pin group and at the number 2 corner in a two-pin group in which one of the pins is common to the row of pins between corners 1 and 2.

It will be observed that the pins are not centered on the frame but are placed closer to the inner than to the outer boundaries thereof; also that the center pin of each three-pin group is

2. **directly opposite the space between two groups of pins at the opposite side.**

Opposed sides of the frame, 10a and 10b, are bevelled along their margins representing inner margins of the working face of the frame, the bevels being indicated by the numeral 12. Opposed sides 10c and 10d, on the other hand, are each provided with a series of notches along their corresponding margins. Notches 14, between the 10 pin groups, lie immediately adjacent the number 1 pins of the groups (counting from the left in Fig. 1), while notches 15, within the pin groups, are placed between the number 2 and number 3 pins (counting again from the left). Notches 15 14 are of somewhat greater depth than notches 15 and are of greater width at the margin of the frame.

One method of using the device is as follows: position the device so that the number 1 corner 20 is at the lower left. Holding the end of the yarn at the arrow, draw the yarn by hand to the far side in the direction indicated by the arrow. Pass the yarn to the right around the first two pins 16 and 17 and return the yarn to the near side, drawing the yarn out between the second and third pins 18 and 19 at the right of the arrow. Tie the free end of the yarn to the body of the yarn so that the knot lies between these two pins. Next, pass the yarn to the right around pins 19 and 20 and draw to the far side, bringing the yarn out between the first and second pins 21 and 22 in the group directly across. Pass the yarn to the right around the pins 22 and 23 and back to the near side out between the first and second pins 24 and 25 in the next group, around 25 two pins and back, continuing as described until corner 2 is reached. Now turn the device so that corner 2 is to the lower left. Pass the yarn around the first two pins 26 and 27 and go to the 30 opposite side, bringing the yarn out between pins 28 and 29, around pins 29 and 30 and back to the now near side between the first and second pins 31 and 32 in the next group. Continue in this manner until corner 3 is reached, at which time 35 turn the device again so that corner 3 is at the upper left. Pass the yarn through the first and second pins 16 and 17 to the now near side, coming out between the first and second pins 18 and 19. Pass the yarn around pins 19 and 20 and go back to the far side, bringing the yarn out through the open space between pins 17 and 21. 40 Work around pins 21 and 22 and back to the near side, coming out through the open space between pins 20 and 24. Continue in this fashion until 45 50 55

the yarn comes out between pins 33 and 34, at which time the weaving may be begun.

In weaving—measure the amount of yarn which will be required by winding the yarn loosely four and one-half times around the device on the outside of the pins. Break and unwind the yarn and thread the needle (not shown). Insert the needle in the groove 35 between pins 26 and 27, pass the needle over the outside loop, under the next yarn, over the next, under, over, etc., entirely across, and draw the yarn completely through, coming out to the left of pin 28. Pass the yarn around pins 28 and 29, and then back over the outside loop, under the next yarn, over, under, etc., bringing the needle out at the open space between pins 27 and 31. Continue in this manner across the device, ending with the last row of weaving next to the pins and coming out at the notch between pins 36 and 37. Draw the yarn around pin 36 and tie it to the loop already around pin 38. The weave is now complete.

Before removing the square by pushing up from underneath, it should be determined that the strands of yarn are uniformly straight and that the outside strand on each side is snugly against the row of pins. Any irregularity may be straightened out by stroking the fabric with the needle. The squares are easily united to form the desired article by methods known to the art.

It will, of course, be immediately appreciated that variations may be made in the square by using different weights of yarns, winding with one color and weaving with another, winding with two strands of a light weight yarn and weaving with a double strand, etc.

The group spacing of the pins aids greatly in the arrangement of the yarn for weaving, avoiding time-wasting mistakes and imperfectly formed pieces; moreover, the grouping scheme reduces to a minimum the number of pins required and makes it possible for instructions to be more easily followed. Due to the bevelling and notch-

ing, the weave may be accomplished with surprising rapidity, jamming of the needle against the frame being substantially precluded.

Although the frame may be fabricated of wood or the like, in which event the bevelling and notching may be accomplished by machining, it is my preferred practice to manufacture the frame by means of a molding operation utilizing a plastic such as polystyrene, for example.

I claim:

A weaving device including a rectangular frame member carrying on its working face a series of pins following the rectangle of the frame and arranged for the most part in spaced groups of three, two of the opposed sides of the frame member being bevelled along their margins representing inner margins of said face, each of the other two opposed sides being provided along its corresponding margin with a first series of notches disposed between pins of three-pin groups, and with a second series of notches, each of which is disposed adjacent a three-pin group, is spaced from the notch within the group by two pins and is aligned with a notch of the first series in the opposite side of the frame.
